UNITED STATES PATENT OFFICE.

TYLER CALHOUN, OF RIDGETOP, TENNESSEE.

DESIGN FOR A SPOON.

SPECIFICATION forming part of Design No. 34,399, dated April 23, 1901.

Application filed March 18, 1901. Serial No. 51,785. Term of patent 7 years.

To all whom it may concern:

Be it known that I, TYLER CALHOUN, a citizen of the United States, residing at Ridgeway, Robertson county, State of Tennessee, have invented and produced a certain new and original Design for a Spoon, of which the following is a specification.

My design for a spoon is fully illustrated in the accompanying drawings, in which—

10 Figure 1 is a perspective view thereof, and Fig. 2 is a central longitudinal section.

15 The essential feature of my design consists of the spoon having the hood shaped substantially as shown. The bowl is formed with a rounded bottom, from which the sides are gradually curved upwardly and terminate in an edge of oval outline. Extending upwardly from the rear portion of the edge of the spoon is a hood or shield 2, which shield follows 20 substantially the contour of the bowl, while the forward edge of the shield or hood is formed on a symmetrically curved line 3, which merges gracefully into the upper edge 5 of the bowl at 4, and, with said edge, thus 25 constituting an oval opening to the bowl 1.

The handle 6 is in prolongation of the bowl at the rear, merging gradually into the bowl at 7, and extends in a reverse curve 8 a short distance from the bowl, thence in a straight portion which terminates in the broadened 30 end 9, whose surface is slightly curved and whose edges are formed on curved lines which are joined to a curved apex 10 at the tip end of the handle. The bowl and handle thus formed unite to produce a spoon of unique 35 and graceful appearance and constitutes my design.

Having thus described my invention, what I claim, and desire to secure by Letters Patent, is—

40 The design for a spoon, substantially as herein described and illustrated in the accompanying drawings.

45 In testimony whereof I have signed my name to this specification in the presence of two subscribing witnesses.

TYLER CALHOUN.
